UNITED STATES PATENT OFFICE.

WILLIAM WILD, OF BLACKPOOL, ENGLAND, ASSIGNOR OF ONE-HALF TO WEST'S GAS IMPROVEMENT COMPANY LIMITED, OF MANCHESTER, ENGLAND.

HEATING OF VERTICAL RETORTS FOR THE DISTILLATION OF CARBONACEOUS MATERIALS.

1,427,426.

Specification of Letters Patent. Patented Aug. 29, 1923.

Application filed June 5, 1920. Serial No. 386,851.

To all whom it may concern:

Be it known that I, WILLIAM WILD, a subject of the King of Great Britain and Ireland, and resident of Beechwood, Newton Drive, Blackpool, in the county of Lancaster, England, have invented certain new and useful Improvements in Connection with the Heating of Vertical Retorts for the Distillation of Carbonaceous Materials, 10 of which the following is a specification.

This invention relates to vertical retorts for the distillation of coal and like carbonaceous materials and has for its object to provide in a ready and efficient manner 15 for the regulation of the secondary air required for combustion in the combustion chambers around the retorts so that the control of the temperatures in each of the said chambers can be more effectively exercised 20 and without interfering with the conditions existing in the remaining chambers.

The invention comprises the provision of two secondary air inlets to each combustion chamber at each side of the retorts, the one 25 inlet being adjacent the flame orifice and the other at a point midway between the ends of the chamber, the arrangement being such that by reducing the amount of air passed to the gas as it issues through the 30 flame orifice into the chamber, combustion can be effected at the second air inlet and the temperature at the end of the chamber opposite the flame orifice be maintained approximately the same as at the flame orifice 35 end of the chamber.

Referring to the accompanying explanatory drawings:—

Figure 1 is a sectional elevation and Figure 2 a sectional elevation on the line AB 40 of Figure 1 illustrating a retort setting constructed and arranged in accordance with this invention.

Figure 3 is a sectional plan view through the setting on the line CD of Figure 2, but 45 drawn to an enlarged scale.

Figure 4 is a detail view to be herein-after referred to.

The same reference letters in the different views indicate the same parts.

50 In accordance with this invention, the secondary air required for combustion by each of the gas jets in the combustion chambers *a* is drawn direct from the atmosphere

and independently of the supplies for the remaining gas flames. Preferably, each 55 secondary air supply *b* has its own control valve *c* which may be a sliding plate, and extends across and through the division and outside walls *d* of the setting from the side opposite its flame orifice *e* so that the said 60 air becomes heated prior to meeting the gas. To ensure a more even distribution of the heat in the combustion chambers *a*, I employ two secondary air inlets *b*, *f* at the opposite sides of each row of retorts *g*, the 65 one inlet *b* being adjacent the flame orifice *e* and the other approximately midway between the ends of the chamber *a* so that by reducing the amount of air admitted by the port *b* and passed to the gas at *e* as it issues 70 into the chamber, combustion can be effected at the second air inlet *f* and the temperature at the ends of the chambers opposite the flame orifices *e* be maintained approximately the same as at the gas inlet end of 75 the chamber. I thus obtain a more uniform heating of the various retorts of a setting. The waste gases leave the chambers *a* at the ports *h*. The gas burnt at the orifices *e* is obtained from the producer *i* and 80 travels up the setting by the passages *j*.

The air supply for the secondary air passages *f* which lead to points midway between the ends of the combustion chambers *a* is preferably obtained from the end of 85 the setting at which the gas orifices *e* are situated as shown so that the air is heated by travelling in contact with the walls of the chambers *a* at the part where the gas flames issue. The abstracted heat is returned to the combustion chambers at the 90 end away from the flame orifices and assists in equalizing the combustion chamber temperatures.

The secondary air passages *b* and *f* serve 95 to assist the brickwork of the combustion chambers *a* in withstanding the high temperatures now usual when steaming of the retorts is practised. Further, the use of two secondary air passages as *b* and *f* for 100 such gas inlet *e* prevents local overheating adjacent the gas orifice.

When steaming is practised, the steam may be passed down the setting through 105 passages *k* formed in blocks *m* disposed between the retorts where it will be highly

superheated. It enters the retorts by the inclined passages *n*, see Figure 4, which are situated adjacent the base of the retort.

My improved arrangement of independent secondary air passages is particularly advantageous where steaming of the retorts is practised and enables the whole length of the retort to be utilized for carbonizing purposes.

Having now described my invention what I claim as new and desire to secure by Letters Patent is:—

In means for the distillation of carbonaceous materials, in combination, a row of vertical retorts, superposed horizontal combustion chambers disposed around the said retorts for heating the latter, each row of

retorts being heated in any one horizontal plane by two chambers arranged at its opposite sides, gas inlets to said chambers at one end of the row of retorts, air supply conduits extending along the whole horizontal length of the combustion chambers to adjacent said gas inlets, further air supply conduits extending along a portion only of the horizontal length of the combustion chambers and each entering one of the latter at a point between its ends, and a waste gas outlet from each combustion chamber at the end thereof opposite to the gas inlet, as set forth.

In testimony whereof I have signed my name to this specification.

WILLIAM WILD.
